FUEL FEEDING APPARATUS WITH
VIBRATORY HOPPER

Hugh McDonald Thomson and Charles Ernest
Mudie, St. Catharines, Ontario, Canada, as-
signors to Foster Wheeler Corporation, New
York, N. Y., a corporation of New York

Application January 25, 1947, Serial No. 724,438

11 Claims. (Cl. 222—161)

1

This invention relates to fuel feeders and more particularly to agitators for mechanical stokers.

The present invention provides an agitator by which a hopper of a mechanical stoker is agitated so that fuel from the hopper will be fed continuously to the fuel delivery mechanism which delivers fuel to a furnace.

This invention further provides an agitator for agitating the fuel in a hopper of a mechanical stoker which agitator is actuated by the fuel delivery mechanism so as to assure proper flow of the fuel to said delivery mechanism prior to the feeding of the fuel to a furnace by said mechanism.

The invention will be understood from the following description when considered in connection with the accompanying drawings forming a part thereof and in which:

Fig. 1 is a longitudinal sectional view taken on the line 1—1 of Fig. 2;

Fig. 2 is a sectional view taken on the line 2—2 of Fig. 1, and

Fig. 3 is a view somewhat similar to Fig. 1 but of another embodiment of the invention.

Like characters of reference refer to like parts throughout the several views.

Referring to the drawings, the apparatus of the present invention comprises a hopper 10 having an inclined rearward wall 11, a substantially vertically extending forward wall 12 and opposite side walls 13 and 14. The hopper is open at the top thereof and also at the bottom thereby providing respectively an inlet through which fuel is introduced into the hopper and an outlet through which fuel will pass from the hopper.

As shown in Figs. 1 and 2, hopper 10 has rollers 15 and 16 adjacent the rearward wall 11 and similar rollers 17 adjacent the forward wall 12. Roller 15 is rotatably mounted in a roller support 18 which support is secured to side wall 13, while roller 16 is similarly mounted in a roller support 19 secured to side wall 14, said rollers being mounted for rotation on shafts which extend in a substantially horizontal plane. Rollers 17 are rotatably mounted in supports 20 secured to opposite side walls 13 and 14 respectively. The rollers 17 and supports 20 are so mounted in relationship to said side walls that the shafts upon which the rollers rotate extend in a plane inclined to the horizontal, as shown more particularly in Fig. 1. Hopper 10 is supported on a track structure which comprises a rail 21 on which the rollers 15 and 16 rest and a rail 22 parallel to rail 21 with which the rollers 17 cooperate. Rollers 17 rest upon guide member 23 associated with

5 rail 22 which guide member is substantially co-extensive with the rail 22 longitudinally thereof. The rails 21 and 22 are mounted on a supporting member 24 secured to the upper portion of a hollow cylindrically-shaped ram casing 25 at the end thereof adjacent a furnace. As shown, a cylinder 26 is formed integrally with the ram casing at the end thereof opposite the end on which the supporting member 24 is secured. Supporting member 24 has a passage 24' therein in communication with the outlet at the bottom of hopper 10 and with the interior of ram casing 25.

10 A ram 27 is slidably mounted within casing 25 and is secured to one end of a shaft 28 through a fitting 29. Shaft 28 at the opposite end thereof has a piston 30 mounted thereon which piston is secured to the shaft by a nut and is maintained in fluid-tight relationship with cylinder 26 by means of packing 32 and a gland nut 33. Piston 20 30 slidably engages the inner periphery of cylinder 26 in a fluid-tight manner. Cylinder 26 has a port 34 at one end and at one side thereof and another port 35, indicated by dot and dash lines 25 Fig. 1, at the opposite end and at the opposite side of cylinder 26.

20 A substantially vertically extending cam pin 36 is positioned so as to extend through the ram and the fitting 29 and project outwardly of ram casing 25 at the top and at the bottom. Pin 36 moves longitudinally of the casing 25 in a slot 40 in the upper portion of said casing and in the slot 41 in the lower portion thereof. The casing has flat surfaces 41' at the outer periphery thereof of adjacent opposite sides of the slot 40 to provide a track for rollers 37 and 38 which are mounted on opposite sides of cam pin 36 on a shaft 39 which extends transversely of said pin.

30 Actuating mechanism which cooperates with cam pin 36 and rollers 37 and 38 is mounted on the upper portion of casing 25 adjacent the lower end of inclined wall 11 of hopper 10 and is adapted to act upon the hopper to move the same. The actuating mechanism comprises a rocker arm 42 having a projection 51 extending therefrom intermediate the opposite ends thereof and a roller 43 rotatably mounted at one end thereof which end normally extends into the path of movement of cam pin 36 so as to be engaged by the top of said pin to thereby actuate arm 42. The opposite end of arm 42 is loosely mounted on a shaft 44 rotatably mounted in supporting members 45 and 46 on opposite sides of slot 40. The supports 45 and 46 are secured respectively to lugs 47 and 48 on the upper part of casing 25. A cam lever 49 also is secured on shaft 44 to rotate

therewith. Lever 49 has an extension 50 disposed above projection 51 on arm 42. An adjusting screw 52 is mounted in projection 51 and cooperates with extension 50 so that the relationship of the arm 42 on roller 43 to cam pin 36 and rollers 37 and 38 may be adjusted to regulate the extent of movement of hopper 10 by said actuating mechanism. As will hereinafter be fully described, roller 53 is rotatably mounted in lever 49 above extension 50 and cooperates with actuated member 54 which is secured to inclined wall 11 of hopper 10.

As shown, the furnace with which the fuel feeding mechanism of the present invention is associated comprises a support 56 which, as shown, is the water leg of a boiler, and is adjacent wall 12 of hopper 10. A retort 58 is disposed beneath water leg 56 and is adapted to receive fuel from ram casing 25 by action of the ram 27. A push rod 59 is secured to the bottom of cam pin 36 and is actuated thereby so that projections thereon, not shown, will move fuel within the retort.

In operation, the ram 27 is reciprocated in a longitudinal direction within ram casing 25 by piston 38 in cylinder 26. Fluid under pressure enters port 34 and causes piston 36 to move to the left, Fig. 1, the fluid in the cylinder to the left of piston 38 flowing outwardly of the cylinder through port 35. When the piston reaches the extent of said movement to the left, valve mechanism, not shown, will interrupt the flow of fluid under pressure into port 34 and permit fluid to be discharged from said port while said valve mechanism will at the same time prevent discharge of fluid through port 35 and will cause fluid under pressure to enter the cylinder through said port. Fluid under pressure entering through port 35 will cause piston 38 to move to the right in cylinder 26, the fluid in the cylinder to the right of piston 38 being exhausted through port 34. This hydraulic reciprocating mechanism for actuating the ram is well-known in the art and it will be understood that ram 27 can be reciprocated by any other means known in the art as well as by the above described well-known hydraulic means.

As shown in Fig. 1, the ram 27 is positioned at the extent of its forward movement, or movement to the left of Fig. 1, and is ready for its return movement or movement to the right, Fig. 1. As the shaft 28 moves to the right moving therewith the ram 27 and ram pin 36 which is guided in slots 40 and 41, the rollers 37 and 38 rotatably mounted on pin 36 engage the portion of arm 42 normally in the path of movement of the pin and said rollers, while the top of the pin 36 engages roller 43. Engagement of rollers 37 and 38 with arm 42 and of pin 36 with roller 43 causes the arm 42 to rotate in a counter-clockwise direction, Fig. 1, the adjusting screw 52 which engages extension 50 on lever 49 causing said lever also to rotate in a counter-clockwise direction so that the roller 53 in said lever engages actuated member 54 on hopper 10 causing the hopper to rise or to be tilted in a counter-clockwise direction. As the hopper is tilted the rollers 15 and 16 on the inclined wall 11 rise above track 21 and pass from engagement therewith, the hopper pivoting in a counter-clockwise direction on guide member 23 through rollers 17. Stop 69 secured to wall 12 and cooperating with rail 22 limits the counter-clockwise or upward movement of the hopper while stop 61 secured to wall 12 and cooperating with rail 22 limits the clockwise or downward movement of said hopper.

As the shaft 28 and pin 36 proceed further to the right, Fig. 1, the arm 42 and lever 49 continue their counter-clockwise rotation until the position indicated in dot and dash lines, Fig. 1, is attained, this position indicating the uppermost point to which the hopper 10 is moved. When the pin 36 moves beyond said dot and dash position, the top of the pin and rollers 37 and 38 pass from engagement with roller 43 and arm 42 respectively and, since support is thereby withdrawn from the hopper, the weight of the hopper rotates lever 49 and arm 42 in a clockwise direction. Withdrawal of the support causes the hopper to move quickly in a downward direction, rollers 15 and 16, which are mounted on the hopper, sharply engaging rail 21 when the hopper reaches the extent of its downward movement thereby jarring the fuel in the hopper causing it to become agitated and pass through the hopper outlet into passage 24' in support 24 thence into ram casing 25 to the left of ram 27 which at this point of the operation thereof has been withdrawn to the right in casing 25 by movement of shaft 28. Upon movement of the shaft 28 to the left, Fig. 1, the fuel which has been jarred into casing 25 and into the path of movement of the ram 27 is moved into retort 58 by said ram. The top of the pin 36 and rollers 37 and 38 engage roller 43 and arm 42 on its movement to the left causing the arm 42 to rotate in a clockwise direction permitting the pin and rollers to pass under the arm and roller 43.

The extent of the rise and fall of the hopper is controlled through adjusting screw 52. By turning the adjusting screw in one direction, the arm 42 is rotated in a clockwise direction moving the extension 50 away from projection 51 on lever 49. The effect of increasing the distance between extension 50 and projection 51 is to increase the amount the hopper 10 will be raised by the actuating mechanism because the distance between roller 43 on arm 42 and roller 53 on lever 49 is also increased thereby lengthening the rise of member 54 by the actuating mechanism and increasing the distance the hopper will fall when the pin 36 and rollers 37 and 38 pass from engagement with roller 43 and arm 42. If the adjusting screw 52 is moved in the opposite direction, the distance the roller 53 moves upwardly is decreased since the distance between extension 50 and projection 51 and roller 53 and roller 43 is decreased. Hopper 10 will be moved upwardly to a lesser extent and will, therefore, have a lesser distance to fall providing a less severe jolt when rollers 15 and 16 engage rail 21.

In the embodiment of the invention shown in Fig. 3, the hopper 10, instead of being mounted on rollers as in the form of the invention illustrated in Figs. 1 and 2, is positioned in a boot 62 having a forward wall 63 which engages forward wall 12 of the hopper and extends downwardly into passage 24' of supporting member 24. Wall 63 has a lug 64 adapted to contact the top of supporting member 24 and limit movement of the boot 62. Side wall 13 of hopper 10 engages a side wall 65 of boot 62 while opposite side wall 14 of the hopper engages an opposite side wall of the boot, not shown, which is similar to wall 65. Boot 62 has an inclined rearward wall 66 with an extension 67 engaging the rearward wall 11 of hopper 10, the rearward wall 66 having a projection 68 extending longitudinally thereof at the bottom of said wall. The projection 68 engages the top of supporting member 24. Boot 62 is movably mounted on supporting member 24 by trunnions 69 which extend outwardly from

the opposite side walls of the boot and are rotatably mounted in bearings 70 on the top of supporting member 24. Trunnions 69 are positioned adjacent the rearward wall 66 of boot 62.

The operation of the embodiment of the invention shown in Fig. 3 is similar to that of the form disclosed in Figs. 1 and 2. Boot 62 and hopper 10 therein pivot on the trunnions 69 when actuated by the actuating mechanism. When arm 42 is moved in a counter-clockwise direction by the ram pin 36 and rollers 37 and 38, the boot and hopper are raised by engagement of roller 53 of lever 49 with actuated member 54 on boot 62 so that the boot and hopper pivot in a counter-clockwise direction on the trunnions 69. As the rollers 37 and 38 and pin 36 pass from engagement with roller 43 and arm 42, the weight of the hopper and boot through force of gravity causes the hopper and boot to pivot in a clockwise direction since lever 49 and arm 42 will rotate in a clockwise direction as support is withdrawn therefrom. Projection 68 on the boot will sharply engage the top of supporting member 24 when the downward limit of movement of the hopper and boot is reached. The sharp engagement of projection 68 with the top of supporting member 24 jars the fuel within hopper 10 causing the same to be agitated and flow from the hopper into passage 24' of the supporting member. Lug 64 on forward wall 63 of boot 62 prevents the boot from jarring outwardly of the supporting member when the boot moves in a clockwise direction.

Since changes may be made in the forms of the invention selected for disclosure without departing from the principles thereof, it will be understood that the invention is not to be limited excepting by the scope of the appended claims.

What is claimed is:

1. In combination with fuel feeding apparatus comprising a hopper and a fuel feeder, said hopper having a fuel outlet and the feeder comprising a horizontally reciprocal ram, said ram cooperating with the hopper outlet so as to move transversely thereof and feed the fuel away from said outlet upon movement in one direction, a pivotal mounting associated with the hopper and having an axis of rotation extending in a horizontal plane and transversely to the direction of reciprocation of the ram, the relationship of the mounting and the hopper being such that the hopper will normally tend to pivot in a clockwise direction on said mounting by force of gravity, a support cooperating with the hopper and normally supporting the hopper against pivoting in said clockwise direction, a hopper actuator comprising a cam pin movable with the ram, a pivotally mounted cam having one engaging means and other engaging means extending radially from said pivot in different directions, the one engaging means cooperating with said hopper, said other engaging means extending into the path of movement of the cam pin to be acted on thereby, the arrangement being such that the cam is pivoted in a counterclockwise direction upon engagement of the cam pin with said other engaging means thereby causing said one engaging means to support and to move the hopper on said pivotal mounting in a counterclockwise direction away from said normal supporting relationship during a part of the reciprocal movement of the ram and upon another part of the movement of the ram to release the hopper to return in a clockwise direction to said normal supporting position by force of gravity.

2. In combination with fuel feeding apparatus comprising a hopper and a fuel feeder, said hopper having a fuel outlet and the feeder comprising a horizontally reciprocal ram, said ram cooperating with the hopper outlet so as to move transversely thereof and feed the fuel away from said outlet upon movement in one direction,

5 a pivotal mounting associated with the hopper and having an axis of rotation extending in a horizontal plane and transversely to the direction of reciprocation of the ram, the relationship of the mounting and the hopper being such that the hopper will normally tend to pivot in a clockwise direction on said mounting by force of gravity, a support cooperating with the hopper and normally supporting the hopper against pivoting in said clockwise direction, a hopper actuator comprising a cam pin movable with the ram, a pivotally mounted cam having one engaging means and other engaging means extending radially from said pivot in different directions, the one engaging means cooperating with said hopper, said other engaging means extending into the path of movement of the cam pin to be acted on thereby, the arrangement being such that the cam is pivoted in a counterclockwise direction upon engagement of the cam pin with said other engaging means when the ram moves in a direction opposite said one direction after feeding of said fuel away from the hopper thereby causing said one engaging means to support and to move the hopper in a counterclockwise direction on the pivotal mounting away from said normal supporting relationship during a part of the movement of the ram in said opposite direction and upon another part of the movement in said opposite direction but prior to the return movement of the ram in said one direction to release the hopper to return in a clockwise direction to said normal supporting position by force of gravity to engage the support abruptly thereby agitating the fuel therein.

3. In combination with fuel feeding apparatus comprising a hopper and a fuel feeder, said hopper having oppositely disposed walls, one of said walls being downwardly and inwardly sloping and a fuel outlet at the bottom thereof, the feeder comprising a horizontally reciprocal fuel moving means, said feeder cooperating with the hopper outlet so as to move transversely thereof and feed the fuel away from said outlet, a pivotal mounting associated with the hopper and having an axis of rotation extending in a horizontal plane and transversely to the direction of movement of the feeder, the relationship of the mounting and the hopper being such that the hopper will normally tend to pivot in a clockwise direction on said mounting by force of gravity, the pivotal mounting comprising a plurality of rollers on the hopper adjacent the lower portion of the downwardly and inwardly inclined wall and the wall opposite thereto, a rail associated with the rollers of each of said walls and extending in a horizontal plane transversely of the direction of movement of the feeder, the rail associated with the rollers adjacent said opposite wall acting as a pivot for said hopper and the rail associated with the rollers adjacent said inclined wall acting as a support to limit the movement of the hopper in a clockwise direction, a hopper actuator cooperating with the hopper and with the fuel feeder so as to be actuated by said feeder during a portion of its movement, the ac-

tuator being constructed and arranged to pivot the hopper on the pivot rail in a counterclockwise direction upwardly from and out of cooperative relationship with the support, the actuator being in supporting relationship with the hopper during said portion of the movement of the fuel feeder and out of supporting relationship after said portion of movement of the feeder thereby permitting said hopper to move downwardly by force of gravity and abruptly engage said support in said normal relationship.

4. In combination with fuel feeding apparatus comprising a hopper and a fuel feeder, said hopper having oppositely disposed walls, one of said walls being downwardly and inwardly sloping and a fuel outlet at the bottom thereof, the feeder comprising a horizontally reciprocal fuel moving means, said feeder cooperating with the hopper outlet so as to move transversely thereof and feed the fuel away from said outlet, a pivotal mounting associated with the hopper and having an axis of rotation extending in a horizontal plane and transversely to the direction of movement of the feeder, the relationship of the mounting and the hopper being such that the hopper will normally tend to pivot in a clockwise direction on said mounting by force of gravity, a support cooperating with the downwardly and inwardly sloping wall of the hopper and normally supporting the hopper against pivoting in said clockwise direction, a hopper actuator comprising a cam pin movable with the ram, a pivotally mounted cam having one engaging means and other engaging means extending radially from said pivot in different directions, the one engaging means cooperating with said hopper, said other engaging means extending into the path of movement of the cam pin to be acted on thereby, the arrangement being such that the cam is pivoted in a counterclockwise direction upon engagement of the cam pin with said other engaging means thereby causing said one engaging means to support and to move the hopper on said pivotal mounting in a counterclockwise direction away from said normal supporting relationship during a part of the reciprocal movement of the ram and upon another part of the movement of the ram to release the hopper to return in a clockwise direction to said normal supporting position by force of gravity to engage the support abruptly thereby agitating the fuel therein.

5. In combination with fuel feeding apparatus comprising a hopper and a fuel feeder, said hopper having oppositely disposed walls, one of said walls being downwardly and inwardly sloping and a fuel outlet at the bottom thereof, the feeder comprising a horizontally reciprocal ram, said ram cooperating with the hopper outlet so as to move transversely thereof and feed the fuel away from said outlet upon movement in one direction, a pivotal mounting associated with the hopper and having an axis of rotation extending in a horizontal plane and transversely to the direction of movement of the feeder, the relationship of the mounting and the hopper being such that the hopper will normally tend to pivot in a clockwise direction on said mounting by force of gravity, the pivotal mounting comprising a plurality of rollers on the hopper adjacent the lower portion of the downwardly and inwardly inclined wall and the wall opposite thereto, a rail associated with the rollers of each of said walls and extending in a horizontal plane transversely of the direction of movement of the

feeder, the rail associated with the rollers adjacent said opposite wall acting as a pivot for said hopper and the rail associated with the rollers adjacent said inclined wall acting as a support to limit the movement of the hopper in a clockwise direction, a hopper actuator comprising a cam pin movable with the ram, a pivotally mounted cam having one engaging means and other engaging means extending radially from said pivot in different directions, the one engaging means cooperating with said hopper, said other engaging means extending into the path of movement of the cam pin to be acted on thereby, the arrangement being such that the cam is pivoted on said pivot rail in a counterclockwise direction upon engagement of the cam pin with said other engaging means thereby causing said one engaging means to support and to move the hopper on said pivot rail in a counterclockwise direction away from said normal supporting relationship during a part of the reciprocal movement of the ram and upon another part of the movement of the ram to release the hopper to return in a clockwise direction to said normal supporting position by force of gravity to engage the support abruptly thereby agitating the fuel therein.

6. In combination with fuel feeding apparatus comprising a hopper and a fuel feeder, said hopper having oppositely side walls, a forward wall and a downwardly and inwardly inclined rearward wall, the feeder comprising a horizontally reciprocal ram, said ram cooperating with the hopper outlet so as to move transversely thereof and feed the fuel away from said outlet upon movement in one direction, a pivotal mounting comprising trunnions associated with each of said side walls and pivotally mounted in a stationary base so that the hopper has pivotal movement thereon in clockwise and counterclockwise directions, a stop associated with the rearward wall to limit the counterclockwise pivotal movement of the hopper, a support cooperating with the downwardly and inwardly sloping wall and normally supporting the hopper against pivoting in said clockwise direction, a hopper actuator comprising a cam pin movable with the ram, a pivotally mounted cam having one engaging means and other engaging means extending radially from said pivot in different directions, the one engaging means cooperating with said hopper, said other engaging means extending into the path of movement of the cam pin to be acted on thereby, the arrangement being such that the cam is pivoted on the trunnions in a counterclockwise direction upon engagement of the cam pin with said other engaging means thereby causing said one engaging means to support and to move the hopper on said trunnions in a counterclockwise direction away from said normal supporting relationship during a part of the reciprocal movement of the ram and upon another part of the movement of the ram to release the hopper to return in a clockwise direction to said normal supporting position by force of gravity to engage the support abruptly thereby agitating the fuel therein.

7. In combination with fuel feeding apparatus comprising a hopper and a fuel feeder, said hopper having oppositely disposed walls, one of said walls being downwardly and inwardly sloping, and a fuel outlet at the bottom thereof, the feeder comprising a horizontally reciprocal ram, means for reciprocally actuating said ram, the ram cooperating with the hopper outlet so as to move from an open position at one side of

said outlet wherein the ram is out of the path of flow of the fuel from the hopper through the outlet transversely thereof to a closed position at the opposite side of the outlet wherein the ram is in the path of flow of fuel from the hopper through the outlet, said ram thereby feeding fuel away from the hopper outlet, the ram thereafter being returned to said open position by the ram actuating means, a pivotal mounting associated with the hopper and having an axis of rotation extending in a horizontal plane and transversely to the direction of movement of the feeder, the relationship of the mounting and the hopper being such that the hopper will normally tend to pivot in a clockwise direction on said mounting by force of gravity, the pivotal mounting comprising a plurality of rollers on the hopper adjacent the lower portion of the downwardly and inwardly inclined wall and the wall opposite thereto, a rail associated with the rollers of each of said walls and extending in a horizontal plane transversely of the direction of movement of the feeder, the rail associated with the rollers adjacent said opposite wall acting as a pivot for said hopper and the rail associated with the rollers adjacent said inclined wall acting as a support to limit the movement of the hopper in a clockwise direction, and a hopper actuator cooperating with the hopper and with the fuel feeder so as to be actuated by the feeder during said return movement to an open position, the actuator being constructed and arranged to pivot the hopper on the pivot rail in an upwardly direction and into supporting relationship with the actuator and out of cooperative relationship with the support, the actuator being in said supporting relationship with the hopper for a portion of said return movement of the fuel feeder and passing out of said supporting relationship at substantially the same time as the feeder reaches said open position thereby permitting the hopper to drop downwardly on the pivot rail by force of gravity and abruptly engage said support in said normal relationship.

8. In combination with fuel feeding apparatus comprising a hopper and a fuel feeder, said hopper having a fuel outlet in the lower part thereof, the feeder comprising horizontally reciprocal fuel moving means, said feeder cooperating with the hopper outlet so as to move transversely thereof and feed the fuel away from said outlet, a pivotal mounting associated with the hopper and having an axis of rotation extending in a horizontal plane and transversely to the direction of movement of the feeder, said hopper being so mounted on the pivotal mounting as to pivot on said axis of rotation, supporting means cooperating with the hopper and supporting the hopper in a normal supporting position and against pivoting in a downward direction, and a hopper actuator comprising actuating means and actuated means, the actuating means comprising an upwardly extending projection reciprocal with said fuel moving means, the actuated means comprising a cam having a plurality of engaging means projecting therefrom, said engaging means being spaced from one another, one of said engaging means cooperating with said hopper, another engaging means extending into the path of movement of said upwardly extending projection to be acted on thereby, the arrangement being such that the cam is operated in one direction upon engagement of the projection with said other engaging means thereby causing said one engaging means

5 to support and to move the hopper on said pivotal mounting in an upward direction away from said normal supporting relationship during a part of the reciprocal movement of the fuel moving means and upon another part of the movement of the fuel moving means to release the hopper to return in a downward direction to said normal supporting position by force of gravity to engage the support abruptly thereby agitating the fuel therein.

10 9. The apparatus set forth in claim 8 wherein the hopper has oppositely disposed walls, one of said walls being downwardly and inwardly sloping and wherein the relationship of the mounting and the hopper is such that the hopper will normally tend to pivot in a clockwise and downward direction on said mounting by force of gravity.

10 10. The apparatus set forth in claim 8 wherein the hopper has oppositely disposed walls, one of said walls being downwardly and inwardly sloping, and a fuel outlet at the bottom thereof, the pivotal mounting comprises trunnions associated with each of said side walls and pivotally mounted in a stationary base so that the hopper has pivotal movement thereon in clockwise and counterclockwise directions, a stop is associated with the rearward wall to limit the counterclockwise pivotal movement of the hopper, the relationship of the pivotal mounting and the hopper being such that the hopper will normally tend to pivot in a clockwise and downward direction on said trunnions by force of gravity, and wherein supporting means cooperate with the downwardly and inwardly sloping walls and support the hopper in a normal supporting position against pivoting in said clockwise direction.

10 11. In combination with fuel feeding apparatus comprising a hopper and a fuel feeder, said hopper having a fuel outlet in the lower part thereof, the feeder comprising fuel moving means reciprocal in a horizontal plane in a fuel feeding direction and in a direction opposite thereto, said feeder cooperating with the hopper outlet so as to move transversely thereof and feed the fuel away from said outlet upon movement in said feeding direction, a pivotal mounting associated with the hopper and having an axis of rotation extending in a horizontal plane and transversely to the direction of movement of the feeder, said hopper being so mounted on the pivotal mounting as to pivot on said axis of rotation, supporting means cooperating with the hopper and supporting the hopper in a normal supporting position and against pivoting in a downward direction, and a hopper actuator comprising actuating means and actuated means, the actuating means comprising an upwardly extending projection reciprocal with said fuel moving means, the actuated means comprising a cam having a plurality of engaging means projecting therefrom, said engaging means being spaced from one another, one of said engaging means cooperating with said hopper, another engaging means extending into the path of movement of said upwardly extending projection to be acted on thereby, the arrangement being such that the cam is operated in one direction upon engagement of the projection with said other engaging means when said fuel feeder moves in a direction opposite to its fuel feeding direction after feeding the fuel away from the hopper thereby causing said one engaging means to support and to move the hopper on said pivotal mounting in an upward direction away from said normal supporting relationship

75 during a part of the reciprocal movement of the

fuel moving means in said direction opposite its fuel feeding direction but prior to the return movement of the fuel moving means in its fuel feeding direction to release the hopper to return in a downward direction to said normal supporting position by force of gravity to engage the support abruptly thereby agitating the fuel therein.
